UNITED STATES PATENT OFFICE.

HAROLD REEVE DARLING AND HARRY SIGARD ALBERTSON, OF LOS ANGELES, CALIFORNIA, ASSIGNORS TO ROBERT THOMPSON COMPANY, A CORPORATION OF CALIFORNIA.

DESIGN FOR A VEHICLE BODY.

Application filed June 27, 1928. Serial No. 27,299. Term of patent 3½ years.

To all whom it may concern:

Be it known that we, HAROLD REEVE DARLING and HARRY SIGARD ALBERTSON, citizens of the United States, and residents of Los Angeles, California, have invented a new, original, and ornamental Design for a Vehicle Body, of which the following is a specification, reference being had to the accompanying drawing, forming a part hereof.

Figure 1 is a side elevation of the vehicle.
Figure 2 is an end view.

We claim:

The ornamental design for a vehicle body substantially as shown.

HAROLD REEVE DARLING.
HARRY SIGARD ALBERTSON.
